UNITED STATES PATENT OFFICE.

FINLEY E. SILLICK, OF BLACK RIVER FALLS, WISCONSIN.

ROPE-BUCKLE.

1,368,766.

Specification of Letters Patent. Patented Feb. 15, 1921.

Application filed August 28, 1920. Serial No. 406,704.

To all whom it may concern:

Be it known that I, FINLEY E. SILLICK, a citizen of the United States, residing at Black River Falls, in the county of Jackson and State of Wisconsin, have invented certain new and useful Improvements in Rope-Buckles, of which the following is a specification.

This invention relates to rope buckles, and has for an object to provide a device to be attached permanently to a rope end, or otherwise, and to be secured rigidly at any point along the rope where convenience makes it desirable.

15 A further object of the invention is to provide a rope buckle having improved means for quickly and conveniently inserting the rope in the buckle.

20 A further object of the invention is to provide a rope buckle providing means facilitating the tightening of a loop in the rope about an article, a bundle and the like, and when so tightened to secured the rope in such tightened position.

25 Figure 1 is a view of the rope buckle associated with a length of rope shown in top plan with the rope in finally secured position.

Fig. 2 is a view of the device in top plan 30 with the rope inserted in the hook of the buckle in position to be tightened about an article or bundle.

Fig. 3 is a sectional view taken on line 3-3 of Fig. 1.

35 Fig. 4 is a view in side elevation of the buckle and rope.

Like characters of reference indicate corresponding parts throughout the several views.

40 The improved rope buckle which forms the subject matter of this application is adapted to be employed in any size and to operate with rope of any diameter. As indicated in the drawings the rope 10 is secured to the eye 11 in any approved manner. The rope forming a loop 12 is then inserted through the hook of the buckle by simply being passed over the extremity 13. The tongue 14 is now brought into engagement with the U-portion 15 of the buckle and in that position the loop 12 may be drawn tightly about an article or bundle. The lateral offset 16 retains the rope within the hook portion, and when the necessary 50 tension has been exerted upon the article or

bundle, the loose end 17 of the rope is hooked over the extremity 13, and drawn into the space between the tongue 14 and the side of the buckle. The tongue 14 is pivotally secured to the buckle in any approved manner, as by forming a shoulder 18 integral with the buckle structure, and forming an eye 19 in the tongue structure embracing the shoulder 18.

While the use has heretofore been noted as 65 in exerting tension upon an article or bundle for binding purposes, it is obvious that the buckle may be employed in a very great number of positions and for other purposes, and that it will engage and firmly hold the 70 rope at any point at which it is connected. It will therefore serve a multitude of uses. For instance, the loop 12 may be employed to encircle the neck of an animal, using the device as a halter, in which case it is not 75 desirable to exert tension, but to permit the loop to remain of such diameter as to easily encircle the neck. In such use the buckle will hold the loop at its secured dimension without slipping and with continuous security.

The drawing is only by way of illustration and the sizes, proportions and relations of the several parts each to the other are only illustrative and are not limiting in any 85 manner upon the invention or the scope thereof.

I claim,

1. A rope buckle comprising a U-shaped hook, a tongue extending longitudinally of 90 and bearing upon the hook, and a lateral offset extending from the tongue across the interval and proportioned relative to the tongue and hook to engage a rope therebetween.

2. A rope buckle comprising a U-shaped hook, an eye carried upon the buckle opposite the hook, a tongue pivoted to the buckle adjacent to the eye and extending longitudinally and bearing upon the hook. 100

3. A rope buckle comprising a U-shaped hook member having an eye formed opposite the U-bend, a tongue pivoted to the device adjacent to the eye and extending longitudinally of and bearing upon the U-bend and 105 a lateral offset from the tongue.

4. A rope buckle comprising a U-shaped hook member, means to attach a rope at the end opposite the U-bend, a pivoted tongue extending longitudinal of the U and bear- 110

ing upon the bend, and a lateral offset extending from one side of the tongue and bearing upon the hook member.

5. A rope buckle comprising an elongated loop member open at one side, means to attach a rope at one end, a tongue pivoted to the structure and bearing upon the loop at the end opposite the rope attaching means, and a lateral offset extending from one side 10 of the tongue bearing upon the loop structure.

6. A rope buckle comprising an elongated loop member, means to attach a rope at one end of the loop, a tongue pivoted adjacent 15 the rope attaching means extending longitudinally of the loop and bearing upon the end opposite the rope attaching means, a lateral offset from the tongue forming a constricted interval at the bend of the loop 20 structure, and means facilitating the intro-

duction of the rope into the loop with the tongue in operative position.

7. A rope buckle comprising a U-shaped body, a rope attaching means opposite the U-bend, a tongue pivoted adjacent to the 25 rope attaching means, extending centrally along the body and bearing upon the U-bend and means carried by the tongue adapted to maintain a rope in contact with the interior of the U-bend.

8. A rope buckle comprising a U-shaped body, a rope attaching means opposite the U-bend, a tongue pivoted adjacent to the 30 rope attaching means, extending centrally along the body and bearing upon the U-bend 35 and an offset carried by the tongue adapted to maintain a rope in contact with the interior of the U-bend.

In testimony whereof I affix my signature.

FINLEY E. SILLICK.
